UNITED STATES PATENT OFFICE.

IRVING S. MERRELL, OF SYRACUSE, NEW YORK, ASSIGNOR TO MERRELL-SOULE COMPANY, OF SYRACUSE, NEW YORK, A CORPORATION OF NEW YORK.

CONVEYER SYSTEM.

No. 828,477.

Specification of Letters Patent. Patented June 12, 1906.

Application filed November 20, 1905. Serial No. 288,216.

To all whom it may concern:

Be it known that I, IRVING S. MERRELL, of Syracuse, in the county of Onondaga, in the State of New York, have invented new and 5 useful Improvements in Conveyer Systems, of which the following, taken in connection with the accompanying drawings, is a full, clear, and exact description.

This invention relates to an improved conveyer system which is specially adapted for use in large preserving plants and similar manufactorys where it is desired to convey the same or different materials from one department in the basement or lower floor of a 15 building to another department on the upper floor or floors or to other elevated remote parts of the plant where the contents of the buckets are automatically discharged into the hoppers or receptacles of the same or different machines, such as mixers, in which the material is to be further treated.

The specific use to which this system is now applied is in the handling of the different ingredients of mince-meat, which requires that such ingredients be conveyed to the mixers in certain proportions in comparatively quick succession with as little manual labor as possible, so that they may be properly agitated and mixed.

The essential object, therefore, of this invention is to render the operation of conveying these ingredients separately and in definite quantities from one department to some remote part of the plant continuously and automatically and to avoid as far as practicable handling of the material by the workmen, thereby avoiding in a measure any contamination or unsanitary handling of the material by the workmen. This object, more specifically stated, is to extend an endless chain or cable over suitable supporting-drums and idlers from one department where each ingredient is supplied in separate buckets to a remote department or upper part of the plant 35 where such material is to be deposited and to provide this traveling chain or cable with suitable bucket-supports which automatically pick up the filled buckets at the supply-stations and convey them to more remote delivery-stations where they are automatically inverted and at the same time jarred to discharge and entirely free the material therefrom.

A further object is to return the empty

buckets to the place of starting where they 55 are automatically detached from the conveyer, and deposited upon an additional conveyer, and thereby carried to a convenient place for refilling.

A further object is to provide manually- 60 controlled means for causing the buckets to discharge at different places along the line of travel of the loaded side of the endless conveyer chain or cable.

A still further object is to provide means 65 whereby the operation of the entire system may be stopped or started at either the receiving or delivery stations.

Other objects relating to the specific structure of the several mechanisms forming a 70 part of the conveyer system will be brought out in the following description.

In the drawings, Figure 1 is a side elevation of a conveyer system embodying the various features of my invention. Figs. 2 and 3 are 75 sectional views taken, respectively, on lines 2 2, Fig. 1, and 3 3 of Fig. 2. Fig. 4 is a top plan of a portion of the device seen in Fig. 3, showing particularly the mechanism by which the filled buckets are fed to the bucket- 80 supports upon the main conveyer. Fig. 5 is a sectional view taken on line 5 5, Fig. 1. Fig. 6 is an enlarged detail view showing particularly a portion of the main conveyer chain or cable and one of the bucket-supports 85 in position for picking up one of the buckets. Fig. 7 is an enlarged detail view of one of the bucket-supports and adjacent portion of the conveyer-chain, showing the arched portion of the guide or track for raising the bucket- 90 support and its bucket in its transit over the shaft of one of the cable-supporting drums. Fig. 8 is an enlarged inner face view of the return portion of the main conveyer, together with an end view of the auxiliary carrier upon 95 which the empty buckets are delivered or transferred from the main conveyer, and also showing the mechanism for automatically actuating the auxiliary carrier intermittently as each empty bucket is transferred thereto. 100 Fig. 9 is an elevation of the portion of the mechanism seen in Fig. 8, showing particularly the clutch and its actuating means whereby intermittent motion is transmitted to the auxiliary conveyer. Fig. 10 is a trans- 105 verse sectional view taken on line 10 10 of Fig. 1. Fig. 11 is a detail elevation of one of the buckets and its supporting means, show-

ing the mechanism for effecting the discharge of the material therefrom into one of the receiving-hoppers. Fig. 12 is an elevation, partly in section, similar to Fig. 11, showing 5 the bucket in its completely-inverted position. Fig. 13 is a horizontal sectional view through the driving-pulley and its clutch mechanism. Fig. 14 is a top plan of modified forms of interlocking devices for inverting the buckets.

The conveyer system shown is adapted to carry the material in buckets from the lower floor or basement vertically through several floors or stories and thence horizontally a 15 considerable distance to a remote upper part of a building and above one or more hoppers, which are located one in advance of the other in the line of travel of the conveyer and into which the material from the buckets is discharged. I therefore provide an endless conveyer-belt 1, which is coextensive with the distance through which the material is to be conveyed and is supported at the terminal stations by suitable drums 2 and 3, while the 25 intermediate portions at the turns are supported by additional idlers or drums 4, 5, and 6.

The conveyer-belt 1 preferably consists of a pair of similar endless chains or cables of substantially the same length, which are arranged side by side a uniform distance apart sufficient to permit the buckets, as *a*, to play freely between them and are connected at regular intervals by suitable cross-bars or tie-rods 7, from which the buckets *a* are suspended, one from each shaft in a manner hereinafter described, sufficient space being left between the cross-shafts 7 to allow the buckets to swing about their respective axes without friction one with the other.

40 The terminal drums 2 and 3 and idlers 4, 5, and 6 are all revolvably supported upon a suitable framework 8, and each preferably consists of a pair of sprocket-wheels which are spaced apart the same distance as the 45 chains which they support and are usually secured to a cross-shaft having its ends suitably journaled on the frame 8, each cross-shaft and its sprocket-wheels constituting one of the supporting drums or idlers for the 50 main conveyer-belt 1.

I preferably provide a pair of lower terminal drums 2, which are supported in substantially the same horizontal plane some distance apart, one in advance of the other from 55 front to rear, so as to maintain the lower part of the main conveyer-belt 1 in a substantially horizontal position at their lower sides, and thereby facilitate the automatic picking up of the filled buckets and discharge of 60 the empty ones, as will be presently described.

Rotary motion may be transmitted to either of the terminal drums by any power-transmitting device for causing the main 65 conveyer-belt 1 to travel in the direction in-

dicated by the arrow *x*, and for this purpose I have shown a continuously-rotating driving-shaft 9 as provided with a clutch 10 and a loose pulley 11, which latter is connected by a belt 12 to a second pulley 13. This pulley 70 13 is secured to a suitable shaft, which is journaled on the frame 8 and carries a pinion 14, in mesh with a larger gear 15 on the shaft of the drum 3, so as to afford ample power and comparatively slow-driving speed 75 for the main conveyer-belt 1. The action of this main conveyer-belt is controlled by the clutch 10, which is feathered on the driving-shaft 9 and is forced into and out of interlocking connection with the loose pulley 11 by means of a double bell-crank lever 16. This lever may be operated locally; but I prefer to provide means whereby it may be actuated in either direction at different parts 80 of the system, and for this purpose its opposite arms are connected to the ends of a return-cable 17, running horizontally along the horizontal upper portion of the conveyer system and around a suitable sprocket 18, which is also rotatively mounted on the frame 8, the 85 intermediate portion of one side of said cable 17 being attached at 19 to a lever 20 within easy reaching distance from the floor, so that by moving the lever back and forth the cable 17 is drawn endwise and transmits rocking 90 motion to the lever 16 to throw the clutch 10 into and out of action.

The shaft of the sprocket-wheel 18 is connected by gears 20' to a horizontal shaft, upon which is secured another sprocket-wheel 21, 100 and this latter wheel is connected by an endless cable 21' to an additional sprocket-wheel 22, which in turn is actuated by suitable hand-chains 23 and 24 within easy reaching distance from the floor of the lower terminal 105 station of the system.

I have now briefly described a means for manually controlling the action of the main conveyer, the general principle of which is clearly shown in Fig. 1; but it is obvious that it is only one of many mechanisms which may be employed for the same purpose, and it is therefore believed to be unnecessary to enter into a detailed disclosure of any particular controlling device.

115 The main conveyer-belt 1 is adapted to carry a considerable number of loaded and empty buckets simultaneously to and from one or more hoppers or receptacles 25, into which the material from the buckets is automatically discharged in a manner presently described, and to relieve the belt from undue strain I provide suitable outgoing and return tracks or guides 26 and 27, which are rigidly secured to the framework 8 and follow the 120 lines of travel of the outgoing and return sides of the belt to support and guide the buckets while in transit to and from the terminal stations. These tracks or guides are 125 preferably located just inside of but close to 130

the endless chains of the belt 1, and the ends of each cross-shaft 7 are provided with suitable flanged rollers 28, which ride upon and against said tracks and hold the chains of the belt against undue sag or lateral displacement, each cross-shaft being free to rock in its bearings on the conveyer-chains and is provided with a pair of pendent hangers or arms 30, rigid thereon and close to the rollers 28 for receiving and supporting the buckets *a*. The arms 30 of each pair are spaced apart a sufficient distance to receive between them one of the buckets *a*, and their inner pendent extremities are formed with inwardly-projecting bearings 30', open at the top for receiving opposite trunnions 31, which project laterally from opposite sides of the bucket, substantially midway between its ends, but above its horizontal center, so that when the bucket is suspended from the conveyer-belt 1 the preponderance of weight, either loaded or empty, is below its swinging axis or trunnions 31. This manner of suspending the bucket renders it self-balancing and free to swing upon its own axis or trunnions 31 or upon the swinging axis of the arms 30, which operate to normally maintain the bucket in a level or operative position with its open side uppermost.

The buckets *a* are placed by hand upon the upper side of an intermittently-movable bed or endless carrier 33, which is supported by suitable rotary drums 34 upon the lower portion of the framework 3 at the lower terminal station of the system and a sufficient distance below the lower horizontal portion of the main conveyer 1 to permit the buckets *a* to be fed beneath the front terminal drum 2, with their trunnions 31 in the path of the opening sides of the bearings 30' of the upwardly-moving arms 30. The rear end of the carrier 33 is therefore disposed directly beneath the lower front terminal drum 2 of the main conveyer 1 and extends forwardly and downwardly in a slight incline plane, so that the front end of its top side, upon which the buckets are placed, is comparatively low or within easy reaching distance from the floor. This carrier 33 is provided at regular intervals with cleats or abutments 34', against which the buckets are placed and by which they are positively fed to the main conveyer 1, and its movement is synchronized with that of the conveyer 1 to advance each successive bucket one cleat-space as each bucket-carrier on the main conveyer is brought into position to pick it up.

Intermitting motion is imparted from the main conveyer 1 to the auxiliary carrier 33 by means of a rotary spider 35, having a series of—in this instance four—radial arms, the ends of which project into the path of the cross-shafts 7 of the conveyer 1 and are successively engaged by said cross-shaft 7 to rotate the spider one arm-space at a time.

This spider is supported upon a suitable shaft on the main frame 8, directly beneath the lower horizontal portion of the conveyer 1, and is connected by gears 36 to a second shaft 37, from which rotary motion is transmitted to the shaft of the rear drum 34 of the carrier 33 by means of a link belt 38 and sprockets 39 and 40.

It is now clear that the loaded buckets, which are placed by hand upon the carrier 33, are automatically fed one by one into position to be and are picked up by the hanger-arms 30 of each successively-advancing cross-shaft 7 of the main conveyer 1 and are thereby carried upwardly and horizontally to one or the other of the hoppers 25, where they are automatically discharged without stopping and the empty buckets returned to the starting-station and automatically deposited upon a second auxiliary carrier 41.

Each outgoing loaded bucket is caused to swing to a completely-inverted position while passing over the hopper 25, into which its contents are to be discharged, and is while in this completely inverted or tilted position forcibly jarred to free the material which may adhere to its sides, and to accomplish these ends in as simple a manner as practicable each bucket is provided at or near its bottom with one or more spurs or keys 43, (duplicated at each end, so that the bucket is interchangeable and operative with either end foremost,) each spur being adapted to interlock with a rocking tumbler or loop 44 just before the moving bucket reaches its hopper 25, said bucket being also provided with opposite side shoes 45, which ride upon fixed guides 46 to steady the bucket against undue oscillation, and to thereby register its spur or key 43 with its loop 44. This loop 44 is secured to and projects upwardly from a rock-shaft 47 on the frame 8, which is located just at the rear of the hopper 25 and is counterbalanced by a weighted arm 48 to normally retain it in position to receive the spur of an approaching bucket. Each rock-shaft 47 is usually provided with a depending handpiece 49 within easy reaching distance from the floor and may be operated when desired to throw the loop 44 out of the path of the spur 43 of an approaching bucket to allow such bucket to continue to the next succeeding hopper before discharging its contents. Each spur 43 and its duplicate, except when central, are located equidistant from but at opposite sides of the longitudinal center of the bucket, so as to travel in the same line and engage the same loop when the bucket is reversed upon the conveyer-belt.

In this class of conveyers it is desirable to enable the attendant, at the delivery or dumping stations to cause the discharge of the successively-advancing buckets containing the same or different materials into the same or different receptacles along the line of

travel of the outgoing side of the conveyer, and for this purpose each end of the bucket is provided with a plurality of—in this instance two—spurs 43, as best seen in Fig. 10, and 5 each rock-shaft 47 is provided with a corresponding number of loops 44, arranged side by side, as best seen in Figs. 10, 11, and 12, and adapted to be brought successively into the path of movement of one of the spurs on 10 the advancing bucket.

It is now clearly evident that the attendant at either of the receptacles 25 may by 15 means of the handpiece 48 rock the shaft 47 to throw either of its loops 44 into or out of the path of either of the projecting spurs on 20 either of the advancing buckets, it being understood that said loops on the same shaft can only be brought into position one at a time for effecting the inversion or discharge 25 of the bucket with which it may be interlocked and that each shaft may be rocked to such a position as to bring each of its loops out of the path of movement of the spurs of the advancing buckets when it is desired to allow such bucket to pass on to the next receptacle or place of discharge.

Each bucket *a* is provided at its upper front and rear edges near the ends with opposite pairs of shoulders 50, which are equidistant from the swinging axis of the trunnions 31 within the radius or distance between the said trunnions and shaft 7 to permit the bucket to swing under the shaft 7 to an inverted position.

At a suitable distance in the front of each shaft 47 and usually directly over each of the hoppers 25 is a pair of rests 51, which terminate in abrupt vertical shoulders 52 and are adapted to be engaged by the front shoulders 40 of the advancing bucket during the operation of dumping the same.

Assuming that the rock-shaft 47 is adjusted to throw one of the loops 44 into the path of the spur 43 of one of the advancing buckets *a*, then as the bucket is drawn forward by the conveyer-belt 1 and hanger-arms 30 the spur 43 will interlock with and rock the loop 44 forwardly a limited distance, and the continued forward movement of the 50 bucket and interlocking connection between the loop 44 and spur 43 will cause the bottom of the bucket to be tilted rearwardly and upwardly, as best seen in Fig. 11, until the shoulders 50 on the front end of said bucket 55 will be brought more or less forcibly into engagement with the fixed rests or stop-faces 51 and with greater force against the upright abutments 52, thereby giving the bucket a sudden jar to loosen the material therein 60 preparatory to completing the discharge into the underlying receptacle 25. Now as the bucket continues its forward movement the top edges of its sides close to the front shoulders 50 are drawn against the upper edges of 65 the upright shoulders 52, which serve as ful-

crums upon which the bucket completes its swinging movement to an inverted position, thereby raising the spurs 43 vertically out of interlocking engagement with the loops 44 with a minimum amount of resistance until 70 the shaft 7 is engaged by the abutments or limiting-stops 50' on the rear end but near the bottom of the bucket, said limiting-stops 50' being located substantially the same distance from the center of the trunnions 31 as 75 the shaft 7 and being near the bottom of the bucket allows said bucket to swing to a complete inverted position, as best seen in Fig. 12.

During the inversion of the bucket as just described the flexing connections between 80 the shaft 7 and bucket *a* allows the rear end of the bucket to swing forwardly and downwardly with greater or less rapidity, thus bringing the limiting-stops 50' against the shaft 7 with considerable force and giving the 85 bucket a second forcible jar while in an inverted position to loosen and free any adhering material therefrom, so that after discharging its contents into the underlying 90 hopper or receptacle 25 the empty bucket is 95 drawn forwardly by the conveyer-belt 1 until it is disengaged from the upper edge of the abutment 52, whereupon the bucket *a* and its supporting-arms 30 swing to their normal upright positions, as best seen in Figs. 1 and 10, the empty bucket being carried back by the return side of the conveyer to the starting-station, or rather to the auxiliary carrier 41, and each bucket is provided with bottom straps *a'* to permit them to be stacked 100 one upon the top edges of another.

Just before reaching the limit of its return downward movement the bucket *a* encounters and rests upon the endless bed 41, and the continued downward movement of the 105 free ends of its supporting-arms disengages the bearings 30' from the trunnions 31, leaving the depending ends of the arms free to swing clear of its bucket.

As soon as the bucket is deposited upon the 110 bed or carrier 41 and the free ends of the arms 30 begin their forward movement with the lower horizontal portion of the conveyer 1 the free ends of said arms, which are provided with roller-bearings 28', engage and trail 115 upon an upwardly-inclined cam-track 27', the forward ends of which are deflected upwardly at 27" in substantially vertical lines nearly tangential to the front faces of the front terminal drums 2 or at about the point 120 where the conveyer-belt 1 begins its ascent. The object of these upwardly-turned extremities 27" of the cam-track 27' is to guide the free ends of the arms 30, or rather the open-sided bearings 30' of the said arms, into 125 registration with the trunnions 31 of the loaded bucket which is to be picked up and carried to its destination, it being understood that the bucket has previously been fed by the carrier 33 into a position with its trunnions 130

31 in the path of the upwardly-moving open-sided bearings 31', which therefore interlock with the trunnions 31 and lift the conveyer from the feeding-carrier 33 and carry it upwardly and horizontally along the outgoing track 26 to the hopper, into which the contents of the bucket are emptied in the manner previously described.

The means for automatically disengaging the returned empty buckets and depositing them on the auxiliary carrier 41, is best shown in detail in Figs. 8 and 9, in which it will be seen that one end of the carrier 41 is located directly beneath the terminal drum 2 at the return side of the conveyer 1 and in the path of the descending bucket, so that the bottom of the bucket encounters and rests upon the top sides of the carrier 41 before its hanger-arms 30 reach the limit of their downward movement, and therefore the continued downward movement of the arms causes the open-sided bearings to fall out of interlocking connection with the trunnions 31, thus leaving the bucket free on the carrier 41, the bucket being guided in its descent by a fixed track m, Fig. 8.

Now as the shaft 7, from which the bucket has just been released, continues to travel around the lower side of the return-drum 2 it encounters and rocks upwardly a cam-lever 54, which is pivoted at 55 to the frame 8 and has its free end connected by an upright link 56 to a pawl 57. This pawl normally engages a tooth 58 of a rocking disk 59, having rigid therewith oppositely-projecting arms 60 and 61, one of which, as 60, is connected by a link 62 and bell-crank lever 63 to a clutch 64, which controls the action of the carrier 41, while the other arm 61 projects into the path of the downwardly-moving cross-shafts 7 to be engaged thereby for restoring the disk 59 and clutch 64 to their normal inactive positions.

The clutch 64 is feathered upon a shaft 66 and is movable into and out of locking connection with a sprocket-wheel 67, which is loose on said shaft 66 and is connected to and driven by a chain belt 68 from the front terminal drum 2 of the conveyer 1. The shaft 66 is geared to an additional shaft 70, and motion is transmitted from this latter shaft to the auxiliary carrier-belt 41 by means of a chain belt 71.

Now when the pawl 57 is released from holding engagement with the disk 59 the weight of the link 62, aided by a spring, if necessary, causes said link to fall, thereby rocking the disk 59 in the direction indicated by arrow y and at the same time rocking the lever 63 to throw the clutch 64 into locking connection with the rotating sprocket-wheel 67, thereby transmitting motion to the shafts 66 and 70 and thence through the medium of the chain belt 71 to the carrier 41, which conveys the empty bucket away from the re-

turn side of the conveyer 1 to some convenient locality where it may be taken and again refilled. This movement of the carrier 41 continues until the arm 61 is engaged by one of the cross-shafts 7 on the returning side of the conveyer 1, which restores the disk 59 and clutch 64 to their normal positions and allows the pawl 57 to drop into holding engagement with the tooth on said disk, ready for the repetition of the operation just described, it being understood that as soon as the clutch 64 is thrown out of action the movement of the carrier 41 ceases.

The operation, briefly stated, is as follows: The filled buckets are placed by hand upon the auxiliary feeding bed or carrier 33 and are conveyed to a point directly under the front lower terminal drum 2, where they are picked up by the traveling hanger-arms 30 and are carried upwardly and thence horizontally along the outgoing track 26 until the spur 43 of one of the advancing buckets encounters the loop 44, which may be in the path of such spur and which being on a fixed axis holds the bottom of the bucket and causes it to tilt upwardly while the top is being drawn forwardly and downwardly until the shoulders 50 strike the rest 51 and abutment 52, which jars the bucket with greater or less force to loosen its contents. As the forward movement of the bucket continues its upper edges become fulcrumed on the upper edges of the abutments 52, thereby causing a further tilting of the bucket to a complete inverted position and withdrawing the spur 43 vertically from its loop 44 until the limiting-stops 50 strike the shaft 7 with sufficient force to further release any material adhering to the sides of the bucket, which as soon as it leaves the abutments 52 returns by gravity to its normal upright position. The empty bucket is then returned along the return-tracks 27 to the auxiliary delivery-carrier 41, where the buckets are automatically detached from their supporting-arms 30 and are conveyed from beneath the return-drum 2 to some locality where they may be taken and refilled, the action of the auxiliary conveyers 33 and 41 being intermittent and synchronized with the movement of the main conveyer 1, so as to pick up a filled bucket as each set of carrier-arms are presented at a certain point along the outgoing side of the conveyer, while the empty buckets are released and carried away as each of the hangers are presented at a certain point in the return side of the conveyer 1.

In Fig. 14 I have shown a series of—in this instance three—dumping-stations at which are located a corresponding number of rock-shafts 47', similar to and for the same purpose as the rock-shafts 47, (seen in Figs. 1, 10, 11, and 12,) except that they are provided with different locking elements or tumblers e, f, and g, which are adapted to be engaged, re-

spectively, by companion locking elements or keys e' , f' , and g' , each adapted to interlock with or fit in its respective tumbler as the buckets are fed along in sequence to the successive stations.

It is obvious that various forms of keys and tumblers may be employed whereby the key of each bucket will automatically interlock with its companion tumbler to effect the inversion or dumping of each bucket at a different station, and in the locking device shown in Fig. 14 the tumblers e , f , and g project from their respective shafts 47' and are provided with openings h , i , and j , respectively, of progressively-increasing widths and are also formed with shoulders k , with which their companion keys e' , f' , and g' are adapted to become interlocked as the buckets a reach their respective stations.

The locking element, as g , of the final or last station of the series may have its free end closed; but the free end of the other locking members e and f are provided with slots l and l' of progressively-increasing widths, leading from their respective openings h and i , the keys e' , f' , and g' being of substantially the same or slightly less widths than the openings h i j of their companion locking members e , f , and g , while the slots l and l' are of less width than their companion keys e' and f' .

The locking elements e , f , and g normally project in a plane above the plane of movement of the keys e' , f' , and g' and are of progressively-diminishing widths corresponding to the progressively-diminishing widths of the keys e' , f' , and g' —that is, the locking members f and g are of less width than the key e' , which engages the locking member e , and the key f' is of greater width than the opening j in the locking member g , while the slot l is of less width than the width of the keys f' and g' , and the slot l' of the locking member j' is of less width than the key g' —so that as the buckets advance in sequence the keys g' and f' will successively ride through the slots l and l' , thereby causing said keys g' , f' , and e' to successively enter the openings j i h , causing the key g' to engage and interlock with the locking member g to invert the bucket at this station, while the keys f' and e' successively interlock with their respective locking members f and e to invert their respective buckets at the latter stations successively. It therefore follows that each key of each bucket automatically selects and engages a different locking member at a different station for inverting and discharging the buckets at different points in their travel, as in this instance the first advancing bucket is discharged at the last station, the second bucket at the next to the last station, the third bucket at the next station, and so on, the key of the buckets following that which is engaged and inverted by the locking member at a certain station operat-

ing to ride upon and depress that and all the locking members of the succeeding stations against the action of their counterweights 48.

What I claim—

1. In a conveyer system, an endless belt 70 having a series of cross-shafts each provided with a pair of swinging bucket-hangers having open-sided bearings, buckets supported in said bearings, an endless carrier below a portion of the return side of the endless belt 75 and upon which the buckets are successively deposited, and means for intermittently moving said carrier as each bucket is successively deposited thereon.

2. In a conveyer system, a main conveyer-belt having a series of cross-shafts each provided with a pair of swinging bucket-hangers, buckets detachably supported in said hangers, means for driving the belt, means for feeding the buckets successively into the 85 path of the hangers to be picked up by said hangers, means for inverting the buckets in said hangers to dump the same, and intermittently-moving means coacting with and actuated by the movement of the conveyer-belt 90 to detach the empty buckets from their hangers and to convey them away from the place at which they were detached.

3. In a conveyer system, an endless conveyer-belt, an intermittently-movable 95 bucket-carrier for successively feeding the buckets one by one to the conveyer-belt, separate devices on the conveyer-belt for picking up the buckets as they are successively fed thereto, different locking elements arranged at intervals along the line of travel of the buckets, each bucket having a different locking element adapted to interlock with only one of the first-named locking elements for inverting and dumping the bucket while 105 in transit.

4. In a conveyer system, a conveyer-belt and buckets detachably supported at intervals thereon, in combination with intermittently-moving means coacting with and actuated by the movement of the conveyer to detach the empty buckets from said conveyer and to convey them away from the place at which they were detached. 110

5. In a conveyer system, an endless conveyer and actuating means therefor, bucket-supporting hangers upon the conveyer, mechanism actuated intermittently by and moving in synchrony with the conveyer for feeding the buckets one by one into said hangers 120 as they are successively presented at a certain point.

6. In a conveyer system, an endless belt having swinging bucket-supporting hangers thereon and means actuated intermittently 125 by said belt for feeding the buckets one by one into said hangers as they are successively presented at a certain point.

7. In a conveyer system, an endless conveyer and actuating means therefor, bucket- 130

supporting hangers on the conveyer having open-sided bearings for receiving portions of the bucket, and intermittently movable means actuated by the conveyer to feed the buckets into position to be picked up by the said hangers.

8. In a conveyer system, a conveyer-belt composed of a pair of endless chains spaced apart side by side and cross-shafts connecting said chains, terminal supporting-drums for said belt, a bucket-supporting hanger suspended from each of said shafts and each provided with a pair of open-sided bearings also spaced apart for receiving and supporting the bucket and a bucket swinging in said bearings, each shaft being located in the path of the overturning side of the bucket.

9. In a conveyer system, a main conveyer-belt having a series of bucket-supporting hangers attached at intervals thereto and each provided with open-sided bearings which are brought into position at a certain point in the travel of the conveyer to automatically pick up a bucket, means actuated by the conveyer-belt to feed the buckets one by one into the path of said open-sided bearings, whereby the loaded buckets are conveyed upwardly, means for inverting the buckets while in transit, and a movable carrier in the path of the return empty buckets for receiving and supporting said buckets and allowing the open-sided bearings to automatically disengage therefrom as the conveyer-belt continues to move.

35 10. In a conveyer system, an endless conveyer having bucket-supporting hangers attached at intervals thereto, tracks or guides running along the outgoing and return sides of the conveyer, rollers on the conveyer traveling along said tracks, intermittently-moving means actuated by the conveyer for feeding the filled buckets into the path of the hangers whereby they are picked up and carried by the outgoing side of the conveyer, means for automatically inverting and discharging the filled buckets while in transit, and additional means for stopping the empty buckets on their return whereby their hangers are disengaged.

50 11. In a conveyer system of the class described, a traveling bucket-carrier a bucket pivotally connected to the carrier automatic means for inverting the bucket during its travel and means for engaging and abruptly stopping the overturning of the bucket.

12. In a conveyer system of the class described, a traveling bucket-carrier, a bucket pivotally connected to said carrier, automatic means for inverting the bucket at a predetermined point in its travel and while in transit, and means on the carrier in the path of the overturning part of the bucket to engage and abruptly stop its overturning movement.

65 13. In a conveyer system of the class de-

scribed, a traveling bucket-conveyer and mechanical means controlled at will to engage and invert the bucket while in transit and additional means in advance of the first-named means to engage the bucket and detach it from said first-named means.

14. In a conveyer system of the class described, a traveling bucket-carrier and buckets pivotally connected thereto and each having a locking member, means in the path of said member to interlock therewith and to invert the bucket while in transit, said means being movable at will into and out of the path of said member and a stop on the conveyer in the path of the overturning bucket to broadly limit such overturning movement.

15. In a conveyer system of the class described, a traveling bucket-carrier, means normally in but movable out of the path of the carrier mounted upon a fixed support for engaging and inverting the bucket, and additional means engaging the overturning part of the bucket for abruptly checking the tilting movement of the bucket when brought to an inverted position.

16. In a conveyer system of the class described, a traveling bucket-carrier, manually-shiftable means in the path of the bucket to tilt the same while in transit, a fixed abutment in advance of said means and engaged by the traveling bucket for further tilting the same to a complete inverted position, and an additional abutment on the carrier engaged by the overturning part of the bucket when brought to an inverted position.

17. In a conveyer system of the class described, a traveling carrier and swinging bucket thereon having a key or spur on each end to permit either end to be arranged foremost, manually-movable means in the path of the key or spur to engage the latter and tilt the bucket toward an inverted position, a fixed abutment also in the path of the bucket at one side of the spur for engaging and completing the inversion of the bucket, and additional means on the carrier engaged by the overturning part of the bucket to stop its swinging movement when brought to an inverted position.

18. In a conveyer system of the class described, an endless conveyer-belt and swinging hanger thereon, a bucket pivotally supported upon the hanger, means in the path of the bucket to engage at one side of its pivot and rock the same to an inverted position, and additional means engaging said bucket at the opposite side of its pivot for stopping the swinging of the bucket upon its pivot with a sudden jar when brought to an inverted position.

19. In a conveyer system, a pair of endless conveyer-chains traveling side by side, a tie-rod connecting said chains, a hanger mounted on the tie-rod, a bucket pivotally mounted

130

upon the hanger and provided with a locking member, means in the path of said member to engage the same and rock the bucket upon its pivot, a fixed abutment for engaging the bucket and tilting it to an inverted position, and a stop-shoulder on the bucket swinging against the tie-rod when said bucket is brought to an inverted position.

20. In a conveyer system, a traveling conveyer-belt having a series of pairs of swinging hangers arranged one in advance of the other, buckets each supported in one of the pairs of hangers each bucket having a locking member attached to its bottom, separate locking members arranged one in advance of the other in the line of travel of the locking members of the buckets to interlock with those on the buckets and tilt said buckets to an inverted position, said separate locking members being movable out of the path of those on the buckets to prevent the dumping of the latter.

21. In a conveyer system, a traveling conveyer-belt and a bucket carried thereby and provided with a plurality of locking members, and separate devices arranged one in advance of the other in the direction of travel of said bucket, each of said devices being located in the path of one of said locking members to engage the same and tilt the bucket, each device being movable into and out of operative position whereby the bucket may be allowed to pass one of the devices and still be tilted by the next device.

35. 22. In a conveyer system, a traveling conveyer-belt and a series of swinging buckets carried thereby, each bucket being provided with a plurality of locking members, and separate tripping devices, each movable into and out of the path of one of said locking members to interlock therewith and rock the bucket upon its swinging axis.

23. In a conveyer system, a bucket, and traveling conveyer-belt having means thereon to automatically pick up the bucket and carry it forward, means in the path of the bucket to engage and tilt the same to an inverted position while being carried forwardly by the belt and additional means to automatically disengage the bucket from the conveyer-belt.

45. 24. In a conveyer system, a traveling conveyer-belt having open-sided bearings, buckets, and means to feed them one by one into said open-sided bearings as the latter are brought to a certain point and additional means mounted on a fixed support to invert the loaded buckets in their bearings, further means to stop the swinging of each bucket 60 when brought to an inverted position.

25. In a conveyer system, a traveling conveyer-belt provided with bucket-supports, buckets journaled in said supports, means for rocking the buckets in said supports to

an inverted position while in transit, and additional means for automatically detaching the empty buckets from the supports at a certain point along the return side of the conveyer-belt.

26. In a conveyer system, a traveling conveyer-belt having swinging bucket-supporting hangers, and buckets thereon, means for inverting the loaded buckets while in transit along the outgoing side of the conveyer, whereby said buckets are emptied, additional means for detaching the empty buckets at a certain point from the return side of the conveyer, an intermittently-movable carrier for receiving the detached empty buckets, and additional means for synchronizing the movement of the carrier with that of the conveyer-belt to actuate the carrier after each successive bucket is deposited thereon.

27. In a conveyer system, a traveling conveyer-belt, means for feeding loaded buckets into proximity to the outgoing side of the conveyer-belt, pick-up devices mounted at intervals upon the conveyer-belt and adapted to pick up the buckets as they are successively fed thereto, means for inverting and thereby discharging the buckets while traveling along and upon the outgoing side of the conveyer, a carrier in the path of the returning empty buckets for receiving and supporting said buckets, whereby the pick-up devices automatically detach themselves from the buckets, and means for intermittently moving said carrier as each successive bucket is deposited thereon.

28. In a conveyer system, a bucket-supporting conveyer-belt, and actuating means therefor, a carrier for feeding the loaded buckets one by one into proximity to the conveyer-belt, means for actuating said carrier intermittently, pick-up devices mounted at intervals upon the conveyer-belt and each operating to pick up one of the buckets as they are successively fed to the conveyer-belt, additional means for inverting the loaded buckets while in transit on the outgoing side of the conveyer, a second carrier in the path of the returning empty buckets for receiving and supporting said buckets, the pick-up devices automatically disengaging themselves from their respective buckets as the latter are successively deposited upon the second carrier, and means for imparting intermitting motion to the second carrier as each bucket is successively deposited thereon.

29. In a conveyer system, a traveling conveyer-belt and swinging buckets thereon, each bucket or series of buckets having a different locking member or key and different locking devices or tumblers located at different points in the line of travel of the bucket and each corresponding to and arranged in the path of one of the keys whereby the key

of each bucket automatically selects and engages its particular locking member independently of the others for inverting its bucket.

30. In a conveyer system, a traveling conveyer-belt and swinging buckets supported thereby, different locking members located at different points in the line of travel of the buckets, and different keys on the buckets each corresponding to and interlocking with one of the locking members separately from the others, whereby each bucket or series of buckets is caused to be inverted at a different point in its line of travel.

31. In a conveyer system, an endless bucket-conveyer, swinging hangers on the conveyer having open-sided bearings, buckets supported in said bearings, an endless carrier having a series of abutments spaced a uniform distance apart for engaging and feeding the buckets one by one into the path of the open-sided bearings as they are successively moved to a predetermined point whereby each succeeding bucket is picked up by each succeeding hanger, and means actuated by the conveyer-belt for moving the feeding-carrier one bucket-space at a time.

32. In combination with an endless conveyer-belt and a series of open-sided bearings mounted thereon, means actuated by said belt for feeding the buckets one by one into position to be picked up by said bear-

ings, means for automatically dumping the buckets while traveling along the outgoing side of the conveyer, and additional means coacting with the return side of the conveyer-belt for disengaging the buckets from said bearings as they are successively returned to a predetermined point. 35

33. In combination with an endless conveyer-belt having a series of cross-shafts each supporting a pair of bucket-hangers, a bucket pivotally mounted in each pair of hangers, means in the path of the bucket for inverting it, and means on the bucket for engaging its shaft when brought to an inverted position. 40

34. In combination with an endless conveyer-belt, open-sided bucket-bearings mounted at intervals upon the belt, buckets supported in said bearings, means for inverting the bucket while in transit along the outgoing side of the belt, an endless carrier coacting with the return side of the belt to disengage the buckets from their bearings, and means actuated by the belt for moving said carrier intermittently as the buckets are successively deposited thereon. 50

In witness whereof I have hereunto set my hand on this 16th day of November, 1905.

IRVING S. MERRELL.
